UNITED STATES PATENT OFFICE.

JESS I. LUBIN, OF SACRAMENTO, CALIFORNIA.

MAIL-ORDER-HOUSE ORDER-BLANK.

1,318,163.

Specification of Letters Patent.

Patented Oct. 7, 1919.

Application filed January 18, 1918. Serial No. 212,396.

To all whom it may concern:

Be it known that I, JESS I. LUBIN, a citizen of the United States, residing at Sacramento, in the county of Sacramento and State of California, have invented new and useful Improvements in Mail-Order-House Order-Blanks, of which the following is a specification.

This invention relates to a mail order house order blank.

It is the principal object of this invention to provide an order blank which is particularly adapted for use by mail order houses and to be furnished the customers, and is provided with means for supplying the mail order house with a self-addressed label and with other means whereby a memorandum of the various items ordered may be separated to be attached to department sales checks and directly forwarded to the department concerned for filling.

In carrying out the present invention I provide duplicate order blanks which are appropriately ruled and designated. The upper of these blanks, or the original, is formed with a carbonized backing, whereby the indicia will be transferred to the second blank, which blank is formed with a series of fields divided by perforations, so that the different parts of the duplicate sheet may be removed and applied to the address label of the package forwarded to the customer and the others to department sales checks, the back of the second blank being gummed for this purpose.

Referring more particularly to the drawings by way of example:

Figure 1 is a view in plan, illustrating the first sheet of the order blank and further indicating its carbonized backing.

Fig. 2 is a view in plan, illustrating the second sheet of the order blank, with one of its corners upturned to indicate its gummed backing.

Referring to the drawings, 10 and 11 indicate sheets of paper, equal in size and integrally connected along one edge, and from which first and second order blanks are formed. Both of the blanks are provided with a suitably lined field, between the lines of which the articles ordered may be designated, as well as descriptive matter and prices. As indicated upon the first sheet 10, a division is made, indicated by the letter A, in which the catalogue number may be written; B is a column in which the quality

of the article and the number of articles may be indicated; and C is a column within which the color of the articles is indicated. A large column is D which provides for the quantity of the article. Following this column are columns E and F within which the price of separate articles and the total cost are written. At the right-hand of the column F is a blank column within which suitable memoranda may be made by the order clerk.

Referring to Fig. 2, it will be seen that the carbonized back of sheet 10 will transfer all of this indicia to corresponding columns on the second sheet 11. The different items upon this sheet, however, are separated by perforated lines 12 which extend the width of the blank. Due to this arrangement the various items may be torn from the blank and separated from each other so that they may be fixed by their gummed back to department sales checks, thus eliminating transcription as is now the practice.

The field above the columns previously described is provided for shipping memoranda. On the first sheet 10 the customer writes his or her name, post-office and other data which would be necessary in supplying a correct address. These notations are transferred to a label field 13 circumscribed by a perforated line which allows the field to be torn from the second sheet 11 and used as a return address label when the order has been filled and a package made. Due to this arrangement, it will be seen that the customer addresses the package and mistakes which might arise from copying the address by the shipping clerk are thus obviated.

In the use of this device, the order blanks are made up attached to the duplicate sheet 11 and are supplied the customer who thereafter fills in the order in the columns designated A, B, C, D, E, and F and the address in the upper field 14. The two sheets are held together preferably along their upper marginal edge and are then forwarded to the mail order house. Upon receipt of the order, the clerk removes the upper order sheet, which comprises a single continuous piece of paper, and thereafter separates the items written upon the second or duplicate order sheet and pastes them by means of the gummed backing upon department sales checks, thus eliminating transcription which is now the universal practice. The label 13 is held until the order is filled and the de-

partment sales checks are forwarded to the various departments concerned. The items on each department sales check which may be collected from a number of orders, are sent to the collecting department and are there segregated by the clerks as they have reference to the original intact order blanks 10 of the various customers. The packages are then made up and the self-addressed 15 gummed labels 18 are applied thereto.

It will thus be seen that by the use of order blanks of this character considerable time will be saved by the clerks of the mail order house through the elimination of 15 transcription and accuracy will be insured, due to the fact that the package label will be addressed by the customer without having been copied and, furthermore, due to the fact that the various department clerks 20 will be furnished with the exact items desired by the customer in the original handwriting. A further advantage is that clerks will no longer be required to copy the various items from the orders upon the 25 different department sales checks as is now the custom.

It will thus be understood that the order blank here disclosed may be arranged with different fields and different columns as occasion arises without departing from the spirit 30 of the invention as claimed.

Having thus described my invention, what I claim and desire to secure by Letters Patent is—

35 1. An order blank comprising a pair of

duplicate sheets upon which an address field and an order field are designated, the fields on one sheet being registrable with the corresponding fields on the other sheet when said sheets are relatively superposed, a carbon 40 backing upon the upper of said sheets, whereby the indicia therefrom may be transferred to the sheet beneath, perforated fields formed upon the second sheet, and a gummed backing upon said sheet, whereby 45 the fields may be separated along the lines of the perforation and applied to other sheets. 2. An order blank comprising a pair of order sheets adapted to be positioned, in relatively superposed relation, an address 50 field indicated upon each of said sheets, a memoranda field indicated upon each of said sheets, the respective fields of said sheets registering when the sheets are superposed one on the other, means whereby the inscriptions made within the fields of the upper sheet may be transferred to the corresponding fields of the under sheet, and perforated 55 lines circumscribing the address field upon the under sheet and dividing the memoranda field of said sheet into individually separable memoranda pieces.

In testimony whereof I have hereunto set my hand in the presence of two subscribing witnesses.

JESS I. LUBIN.
